UNITED STATES PATENT OFFICE.

JUSTIN O. SCHWARZ AND GUSTAF BJORKLUND, OF NEW YORK, N. Y., ASSIGNEES TO
HARDMAN PECK & CO., A CORPORATION OF NEW YORK.

MECHANICAL MUSICAL INSTRUMENT.

1,217,227.

Specification of Letters Patent. Patented Feb. 27, 1917.

Application filed July 14, 1915. Serial No. 39,737.

To all whom it may concern:

Be it known that we, JUSTIN O. SCHWARZ, a citizen of the United States, residing in the city, county, and State of New York, 5 and GUSTAF BJORKLUND, a subject of the King of Sweden, residing at the city of New York, county of Queens, and State of New York, have invented certain new and useful Improvements in Mechanical Musical Instruments, of which the following is a specification.

Our invention relates to playing mechanisms for pianos or other musical instruments in which the action is operated by 15 pneumatic striker-bellows.

The principal object of the invention is to provide means for accenting any desired note or notes of the action.

We attain that object by supplementing 20 the ordinary playing mechanism with a series of auxiliary striker-bellows and means for operating those bellows, whereby to augment the force of the blow with which the accented note or notes are struck.

25 In the accompanying drawings,

Figure 1 is a diagrammatic sectional elevation of a unit embodiment of our invention, the section through the lower left hand portion thereof, representing the valve chest 30 and striker-bellows, being taken on the line *a—a* of Fig. 2;

Fig. 2 is a top plan view of the valve chest and striker-bellows; and

Fig. 3 is an end view of a detached striker- 35 bellows and an associated auxiliary bellows.

The tracker 1, over which the note-sheet (not shown) travels, has a series of note-apertures 2 each communicating through a tube 3 with a primary pneumatic 4 provided 40 with an exhaust chamber 5 and a diaphragm valve 6. A conduit 7 leads from said pneumatic to the air chamber 8 of the corresponding secondary pneumatic 9 which pneumatic is provided with an exhaust 45 chamber 10, a diaphragm valve 11 and a passageway 12 leading from the valve to the striker-bellows 13. The exhaust chambers 5 and 10 are connected by a pipe 14 and are both maintained in a state of air 50 exhaustion, during the playing of the instrument, by means of suitable suction apparatus (not shown) drawing on the pipe 15.

Separate pneumatics and striker-bellows are provided for each note of the action. If desired several of the pneumatics may be 55 combined in a single chest and the chests arranged in tiers in the usual manner.

Appurtenant to each striker-bellows 13 is an auxiliary bellows 16 having an arm 17 which overlaps the movable leaf of the 60 striker-bellows but is not attached thereto. In the ordinary playing of the instrument the striker-bellows 13 operate independently, but when a note is to be accented the striker and the auxiliary bellows thereof operate 65 conjunctly so as to increase the force of the blow with which the striker-arm 18 acts upon the hammer action (not shown) of the note.

The conduit 7 has a branch 19 leading to 70 the air chamber 20 of the pneumatic 21, which pneumatic governs the operation of the auxiliary bellows 16. Said pneumatic is provided with a chamber 22 normally containing atmospheric air, a diaphragm valve 75 23 and a passageway 24 leading from the valve to the auxiliary bellows.

Whenever air is admitted, through the conduit 7, into the air chamber 8 of the secondary pneumatic of the striker-bellows of 80 any note, it will be simultaneously admitted, through the branch 19, into the chamber 20 of the secondary or governor-pneumatic of the corresponding auxiliary bellows. As, however, the chamber 22 of the latter pneumatic normally contains air, the admission of air into the chamber 20 under the diaphragm of the valve 23 will not effect movement of the valve and consequently the auxiliary bellows, controlled by that valve, will 85 remain inert during the normal operation of its companion striker-bellows.

To permit movement of the valve 23 it is necessary to apply suction on the chamber 22. For that purpose we provide a pneumatic device 25 which serves to control the application of suction on that chamber. Said device communicates through a tube 26 with the chamber 22 and through a tube 27 with an accent-aperture 28 in the tracker 100 90 and has its operation controlled by perforations in the note sheet registering with said apertures.

The device 25 preferably consists of a

valve board or chest containing a primary valve 29 and a secondary valve 30 having exhaust chambers 31 and 32 respectively, which chambers are connected by a channel 33 and communicate through a tube 34 with the suction apparatus of the instrument. A passageway 35 leads from the primary valve to the air chamber 36 under the diaphragm of the secondary valve.

Ordinarily all of the secondary or governor-pneumatics of auxiliary bellows of the entire action will be contained in two or more chests each having a single continuous chamber 22 common to all of the valves 23 of the chest. For example two chests may be provided each containing the valves of all of the auxiliary bellows of the bass and treble notes respectively, or said valves may be grouped in any other desired manner. To control the suction on the chamber 22 of each group of valves, a separate pneumatic 25 and aperture 28 will be provided.

In the drawings the various valves are shown in the position they assume when the tracker apertures are covered. Whenever one of the apertures 28 is uncovered air will enter into the corresponding device 25 and cause the primary and secondary valves thereof to rise and establish communication between the exhaust chamber 32 and the chamber 22 whereby to exhaust the air from the latter. Now if air is coincidently admitted, by uncovering a note opening 2, into the air chambers 20 of one or more of the valves 23 those valves will operate to cause collapsing of the auxiliary bellows, simultaneously with the collapsing of the striker-bellows, and thus accent the playing of the corresponding note or notes.

If desired the auxiliary bellows 16 may be employed to increase the sound of the normal playing of the notes instead of for accenting purposes. To that end we provide a valve block 37 consisting of two sections, one slidably on the other, and having in each section channels 38 which connect with the tubes 27 leading from the accent openings to the pneumatic devices 25. The upper section of the block also contains a series of open-ended channels 39. By sliding the sections of the block on each other the air-line 27 may be broken and the pneumatic devices 25 may be placed in continuous communication with the outside air through the open-channels 39. In this condition the pneumatic devices will operate to apply a constant suction on the chamber 22. Now whenever a note-opening 2 is uncovered both the bellows 13 and 16 controlled by that opening will operate together so as to increase the force of the blow of the normal playing stroke of the note.

The construction and arrangement of the various parts may be modified and varied from that illustrated in the accompanying

drawings and described herein without departing from the essential features of this invention.

What we claim as our invention and desire to secure by Letters Patent is:

1. In pneumatic actions the combination, 70 with an independently operable striker-bellows, of an auxiliary bellows carrying an arm which contacts loosely with the movable leaf of the striker-bellows, and means for operating both bellows in unison.

2. In pneumatic actions the combination, 80 with a series of independently operable striker-bellows, of a series of auxiliary bellows each disposed alongside of its companion striker-bellows and having an arm which contacts loosely with the movable leaf thereof, and means for selectively operating any of the auxiliary bellows conjunctly with its companion striker-bellows.

3. In pneumatic actions the combination, 85 with a tracker having a note aperture and an accent aperture, a striker bellows, and means communicating with the note aperture for controlling the striker bellows, of an auxiliary bellows having a member which contacts loosely with the movable leaf of the striker-bellows, and means communicating with both the note and the accent apertures for controlling the auxiliary bellows, said 95 means operating to actuate the auxiliary bellows when air is admitted to both apertures simultaneously.

4. In pneumatic actions the combination 100 of a tracker having a note aperture and an accent aperture, a striker-bellows, an auxiliary bellows arranged alongside the striker-bellows and carrying an arm which contacts loosely with the movable leaf thereof, and means communicating with both apertures 105 for controlling said bellows, said means operating to independently actuate the striker-bellows when air is admitted to the note aperture alone and to actuate both bellows conjunctly when air is admitted to both apertures simultaneously.

5. In pneumatic actions the combination 115 of, a tracker having a series of note-apertures and an accent aperture, a series of striker-bellows; an auxiliary bellows associated with each striker-bellows, pneumatics communicating with each note-aperture and its corresponding striker-bellows for controlling the operation of the latter upon admission of air into the note-aperture, and 120 other pneumatics communicating with the accent-aperture and the auxiliary bellows for selectively governing the auxiliary bellows to co-act with their companion striker-bellows upon admission of air into the accent 125 aperture and one or more of the note-apertures simultaneously.

6. In pneumatic actions the combination 130 of, a tracker having a note aperture and an accent aperture, a striker-bellows, an auxil-

iary bellows, pneumatics communicating with the note-aperture and striker-bellows for operating the latter upon admission of air to the note-aperture, a valve for governing operation of the auxiliary bellows communicating through said pneumatics with the note-aperture, and a pneumatic device communicating with the accent aperture and the valve for applying suction to the valve upon admission of air into the accent aperture, said valve operating to permit exhaustion of air from the auxiliary bellows when air is admitted to both apertures simultaneously.

7. In pneumatic actions the combination, of a tracker having a series of note-apertures and an accent aperture, a series of striker-bellows, an auxiliary bellows for each striker-bellows, a primary and a secondary pneumatic for each striker-bellows, having communication with the corresponding note-aperture, a secondary pneumatic for each auxiliary bellows communicating with the primary pneumatic of its companion striker-bellows, a pneumatic device for applying

10

15

20

suction to all of the secondary pneumatics of the auxiliary bellows upon admission of air to the accent aperture, each of said secondary pneumatics operating to permit exhaustion of air from the corresponding auxiliary bellows when air is admitted to the note aperture of its companion striker-bellows and to the accent aperture simultaneously.

8. In pneumatic actions the combination of a striker-bellows, an auxiliary bellows, a secondary pneumatic for controlling the striker-bellows, a secondary pneumatic for controlling the auxiliary bellows, and a single primary pneumatic controlling the admission of air to both secondary pneumatics.

In testimony whereof, we have hereunto affixed our signatures in the presence of two subscribing witnesses.

JUSTIN O. SCHWARZ.
GUSTAF BJORKLUND.
